CARBURETOR

Ladimir F. Stupecky, Manitowoc, Wis.

Application December 15, 1941, Serial No. 422,965

12 Claims. (Cl. 261—41)

This invention relates to new and useful improvements in carburetors more particularly adapted for use in connection with internal combustion engines and consists in the matters hereinafter described and particularly pointed out in the appended claims.

One of the objects of my invention resides in the provision of a carburetor for internal combustion engines which is efficient in operation in a comparatively long range of varying altitudes 10 without the aid of a fuel pump, or the well known vacuum fuel-supply tank, irrespective of the position of the main fuel supply tank relatively to the carburetor.

Other novel features or objects of my invention 15 may generally be stated as follows:

(a) During the operation of the carburetor, its sealed fuel chamber maintains a constant-level supply of fuel below atmospheric pressure and insures quicker engine acceleration because 20 of the control of the pressure in the fuel chamber directly by the vacuum within the engine cylinder manifold;

(b) Proper proportions of combustible fuel mixtures are supplied to the engine at all engine 25 speeds. During the increase in speed or power of the engine, the proportionate flow of the fuel to the air is relatively slightly decreased so that the combustible mixture is automatically made leaner progressively with the increased speed of 30 the engine with the result that not only fuel economy is attained but also increased power and smooth engine operation;

(c) The automatic control of the proper fuel mixtures for varying engine speeds and the advantages resulting therefrom, as set forth in above paragraph (b), are attained through the 35 interposition of a buoyant fuel-metering receptacle between the fuel supply jets and the fuel supply in the fuel reservoir;

(d) The buoyant fuel-metering receptacle, due to its limited fuel capacity, functions also to prevent flooding of the engine cylinders in quick starting with a closed choke valve; and

(e) A novel means for adjustably varying the cross-sectional area of the venturi is provided through a plurality of telescopically mounted or concentrically disposed plurality of tubes which extend through the carburetor air inlet passage 50 into the zone of the venturi below the main or high speed fuel jet. Through the arrangement of such concentrically nested and removably supported tubes, a standard size of carburetor may be adjustably adapted for operation with several 55

engines of varying piston displacement and varying crank shaft speeds.

With the above and other objects in view, my invention consists in the novel combination, construction and arrangement of the parts and members shown in preferred embodiment in the attached drawing, described in the following specification, and particularly pointed out in the appended claims.

In the drawing:

Fig. 1 is a vertical section through a carburetor embodying my invention;

Fig. 2 is a cross-section taken on line 2—2 of Fig. 1; and

Fig. 3 is a partial vertical section showing the use of shorter restrictor tubes whereby the carburetor shown in Fig. 1 may be adapted for proper air supply in an operation with an engine having an increased piston capacity.

The carburetor, as illustrated in the attached drawing, is provided with an air intake passage 10, which may preferably be provided with an auxiliary or choke valve 11, and a suction or outlet fuel passage 12 provided with a control throttle valve 13.

The valves 11 and 13 are centrally supported on rock shafts and operated by suitable means in the well known usual manner.

The throttle valve 13 and the fuel passage 12 are disposed in the upper member 14 which is cast with a suitable flange 15 for connection to an engine manifold, and the integral ears 16 are adapted to receive suitable cap screws 17 for securing of the upper member to the lower member 18 in which the air inlet passage 10 and choke valve 11 are disposed.

I have preferred to show three screws 17 for securing the member 14 to the member 18 and the proper alignment of these members is insured by preferably providing an annular extension 19 on the lower face of the upper member 14 which is adapted to be positioned in an annular recess 20 formed in the upper face of the lower member 18.

The upper member 14 is so formed that the fuel passage 12 is restricted in diameter near its lower end to form a Venturi throat 21.

The lower member 18 is formed with an integral inverted cup-like extension 22 which is closed at its open lower face with the closure wall 23 and which extension 22 and closure wall 23 enclose the constant-level fuel chamber 24.

The fuel chamber 24 is supplied with fuel through the usual fuel connection 26 controlled by the valve 27. A valve seat clean-out plug 28

is preferably provided in the connection 26 which is a part of the closure wall 23.

The fuel supply is maintained at a constant level by a suitable float 29 in the fuel chamber 24 which is operatively connected to the valve 27 by the forked lever 30, pivoted at 31 between the ears 32, and having its forked end in engagement with the collar 33 on the lower end of the float tubular extension 34 and its opposite ball-like end 35 positioned in a recess of the valve 27.

The float 29 is freely movable up and down upon the pin 36 which extends through the float and its tubular extension 34 and through the closure wall 23 into threaded engagement with the top wall of the extension 22.

A nut 37 on the lower threaded end 38 of the pin 36 is adapted to secure the removable closure wall 23 to the extension 22.

The lower member 18 is formed with a fuel well 39 and, as illustrated in the drawing, this fuel well 39 is preferably disposed between the air inlet 10 and the fuel chamber 24.

The fuel well 39 is provided with a vertical elongated opening 40 to permit free passage of fuel therethrough from the fuel chamber 24, and this fuel well 39 is also provided with an opening 41 to provide communication with the air inlet passage 10. It will be noted that the vertical opening 40 extends above the normal, constant fuel level X of the fuel chamber 24; that likewise the transverse opening 41 is disposed well above the fuel level X, and that the opening 41 is positioned slightly below the Venturi throat 21 wherein the flow of air through the inlet 10 past the opening 41 will create a partial vacuum in the well 39 and in the otherwise sealed fuel chamber 24. Since a partial vacuum is maintained in the fuel chamber 24 during the operation of the carburetor an adequate fuel supply in chamber 24 is assured.

A buoyant fuel-metering receptacle 42 is positioned in the well 39. The fuel-metering receptacle 42 is formed from comparatively thin metal in the shape of a vertically disposed elongated cup-like body of circular cross-section, open at its upper end, and formed at its lower end with a wall 42A having a fuel inlet opening 43 therein. The fuel is supplied from the fuel chamber 24 through the vertically disposed opening 40 into the well 39 and through the opening 43 into the receptacle 42. When the carburetor is in an inoperative state, the receptacle is filled with fuel to a level aligned with the fuel level X of the fuel chamber 24 and the bottom of the receptacle 42 rests on the plurality of small upstanding lugs or projections 44, formed integrally with the upper face of the bottom of the well 39, to insure a free flow of fuel under the bottom of the receptacle 42 and through the inlet opening 43 into the receptacle 42.

The main nozzle, generally indicated by numeral 45, consists of a horizontal tubular jet 46 having a discharge end 47 extended into the center of the Venturi throat 21 and formed with an angularly cut discharge end to present the outlet end of the discharge passage 48 substantially on the vertical center line of the mixing chamber 12 and the Venturi throat 21.

The high speed jet 46 is formed with an enlarged passage 49 and extends into a transverse bored port 50 in the wall of the carburetor upper member 14 and this port 50 is closed by a screw plug 51.

The port 50 is provided with a communicating port 50A extending vertically downwardly and

this port 50A is disposed substantially centrally relatively to the well 39 and metering receptacle 42.

The high speed horizontal jet 46 includes a vertical tubular extension 46A which extends from the port 50, through the port 50A, into the metering receptacle 42 to a point below the fuel level X of the fuel chamber 24.

The carburetor is provided with a low or idling speed fuel outlet port 52 controlled by a fuel-regulating screw-mounted adjustable pin valve 53. The outlet port 52 is supplied by fuel through the vertical port 54 which is connected, at its lower end, with the vertical idling jet extension 55.

If desirable, the port 54 may be provided with a check valve, as for example a metal ball, to positively prevent the flow of the fuel into and through the idling speed outlet port 52 during the operation of the engine when the fuel is being discharged from the nozzle 45.

The idling jet extension 55 is smaller in diameter than the main or high speed tubular jet extension 46A, extends through the center of the extension 46A, and is provided with a horizontal jet extension 55A extending within and centrally of the enlarged passage 49 of the horizontal high speed jet 46.

The vertical idling jet extension 55 extends downwardly below the lower end of the vertical high speed jet extension 46A, is preferably flanged at its lower end, as indicated by numeral 55B, and is provided with fuel inlet slots 25 extending through the flange 55B and into the lower part of the extension 55.

As indicated above, my invention includes novel means for adjustably varying the cross-section of the Venturi throat and same consists in providing an upstanding pin 56 having a flange 57 connected by screws 58 to a bottom portion of the carburetor lower member 18.

As shown in the illustrations, the pin 56 extends into the air inlet passage 10 and its upper end is disposed within the zone of the Venturi throat 21 and, obviously, this pin 56 itself acts as a centrally disposed restrictor for the Venturi throat.

In order to further adjustably variably restrict the Venturi throat 21 so that a standard size of carburetor may be operatively adapted to a number of engines varying in piston displacement, I provide, and support about the pin 56, a plurality of concentrically arranged removable tubular restrictors 59, 60, 61, 62 and 63 in telescoped arrangement about the pin 56.

The upper ends of the tubular restrictors are ground to form a conical face generally indicated by numeral 64, and, as shown assembled in the illustrations, clearly illustrate the maximum restricted venturi for the comparatively smallest engine adaptation. For engines of comparatively greater piston displacements one or more of the tubular restrictors may be removed to proportionately increase the cross-sectional area of the venturi to suit the piston displacement.

When any of the restrictor tubes are removed in adapting the carburetor to engines of greater piston displacement, the removed restrictors are replaced by shorter tubes 59A, 60A and 61A having upper ends ground to fit the contour of the curved wall 10A of the air inlet 10, as illustrated in Fig. 3.

Any suitable means for securing the restrictors 59 to 63 inclusive may be provided. I have preferred to use a cap screw 65 having a pin-like

extension 66 extending through aligned openings near the lower end of the restrictors. The pin-like extension 66 also functions as means for indexing the tubular restrictors for properly positioning the shorter filler restrictors 59^A, 60^A and 61^A with respect to the curved face 10^A of the air inlet 10.

The function of the choke valve 11 is well understood in the carburetor art, however, it may be stated that in a quick engine starting operation, with the choke valve 11 in closed position, the fuel will be forcibly rapidly withdrawn from the metering receptacle 42 through the idling jet extension 55, ports 54 and 52, into the mixing chamber 12. In such quick starting operation, the limited fuel capacity of the metering receptacle 42 is a positive provision for preventing flooding of the engine cylinders.

In normal idling operation with the throttle valve 13 closed, the vacuum in the mixing chamber 12 will draw the fuel directly through the idling jet into the engine manifold and the amount of the idling fuel supply may be adjusted by the valve 53.

In the acceleration of the speed of the engine, as the throttle valve 13 is gradually progressively opened, the flow of the fuel from the discharge port 52 will cease, but fuel will immediately be discharged into the Venturi throat 21 through the high speed jet nozzle 45.

In the initial stages of such progressively increased speed of the engine, the fuel discharged from the high speed jet nozzle 45 will flow from the metering receptacle 42 through the high speed jet extension 46^A and also through the idling jet extensions 55 and 55^A.

During such initial stages of progressively increased engine speed, the fuel will be withdrawn through the extensions 46^A, 55 and 55^A from the metering receptacle 42 slightly faster than it be supplied to the metering receptacle through the opening 43, hence the head pressure of the fuel in the metering receptacle will be gradually progressively decreased as the speed of the engine is progressively increased and while the velocity of the air through the Venturi throat 21 is progressively increased with the result that the combustible mixture will be slightly progressively made leaner.

During these initial stages of operation the fuel level in the metering receptacle 42 will be gradually lowered and the buoyant metering receptacle will be gradually raised in the fuel well 39 and at further advanced stages of increased engine speed the fuel level in the metering receptacle 42 will move to a line below the bottom end of the high speed jet extension 46^A whereupon the supply of fuel to the high speed jet nozzle 45 will be further decreased since the fuel will then be supplied only through the extensions 55 and 55^A.

As the speed of the engine is still further gradually increased the fuel level in the metering receptacle 42 will continue to be gradually lowered within the space between the bottom end of the extension 46^A and the flanged bottom end 55^B of the extension 55; but during such final lowering of the fuel level in the metering receptacle, the bottom 42^A of the metering receptacle 42 will finally be raised into stopped position against the flange end 55^B of the extension 55 before the fuel level in the metering receptacle can possibly pass below such flanged end 55^B, and when the bottom 42^A of the fuel metering receptacle 42 is in stopped engagement with

the flanged end 55^B the fuel will pass through the receptacle opening 43 into the open end of the extension 55 and through the slots 25 thereof.

The opening 43 in the bottom of the metering receptacle 42 is large enough to supply all of the required fuel through both high and low speed jets for all engine speeds.

When the high speed jet extension 46^A ceases to supply fuel to the nozzle 45, due to the fact that the fuel level in the metering receptacle has been lowered to a level below the inlet end of the high speed jet extension 46^A, the flow of the fuel will then in such event continue to be supplied to the nozzle 45 through the low speed jet extension 55 but in such event the fuel level in the metering receptacle 42 will also gradually rise even though the speed of the engine is gradually increased and during such rise of the fuel level in the metering receptacle, the head pressure of the fuel therein will therefore be slightly gradually increased to thus assist in supplying slightly more fuel to the engine during the increased high engine speeds, while at the same time the partial vacuum in the fuel reservoir 22 and in the metering receptacle 42 is slightly increased. The gradual rise of the fuel level in the metering receptacle 42 will continue until the fuel demand of the low speed nozzle 55 is equal to the supply of the fuel passing through the inlet opening 43 in the bottom of the metering receptacle 42 and such balance between the maximum demand and supply of fuel being substantially at the point of maximum engine speed.

From the above description of the operation of my improved carburetor it will be readily understood that the operations of my carburetor are not effected by atmospheric pressure; that the fuel supply for the constant-level fuel chamber is readily maintained and insured by partial vacuum induced therein; that properly proportioned combustible fuel mixtures are provided to meet varied increased engine speeds, through the novel buoyant fuel-metering receptacle in combination with the novel construction and arrangement of the high speed and idling jets; and that the novel removably mounted telescoped restrictors interposed into the air zone of the Venturi throat provide means whereby a standard carburetor may be readily provided which is adapted for use in connection with internal combustion engines of a varying range of piston displacements or engine speeds.

While the drawing and above description is directed to a preferred embodiment of my invention and are solely for the purpose of illustrating an operative embodiment of the invention, I do not wish to be understood as limiting myself to the exact details of construction and arrangement of the parts and members shown and described therein. The invention is particularly pointed out in and defined by the appended claims.

I claim:

1. A carburetor for internal combustion engines including a mixing chamber having a valve-controlled outlet, a restricted Venturi throat below said mixing chamber, an air inlet passage communicating with said Venturi throat, a constant-level fuel reservoir having a float-controlled fuel inlet valve therein, a fuel well disposed adjacent to said fuel reservoir, an open passage providing air communication between said air inlet passage and the upper portion of said fuel well, a second open passage providing both air and fuel communication between said fuel reservoir

and said fuel well; said fuel reservoir and said fuel well being sealed to atmospheric pressure except through said first-named open passage when the carburetor is inoperative but subject to the induction of a partial vacuum therein by the flow of air past said first-named opening during the operation of the carburetor, a buoyant fuel-metering receptacle mounted in said fuel well having an open top and a fuel-inlet opening in the bottom wall thereof, a single fuel-discharge nozzle, a pair of concentrically disposed high speed and idling fuel jet extensions having discharge ends arranged to discharge fuel through said single discharge nozzle into said Venturi throat and opposite ends extending into said fuel-metering receptacle; said idling jet extension, extending below the lower end of said high speed jet extension, an idling fuel outlet port adapted to discharge fuel into said mixing chamber, and a fuel passage connecting said idling fuel port with said idling jet extension, the flow of the fuel from said fuel-metering receptacle being adapted to be successively discharged through said idling fuel outlet port, thence through said pair of concentrically disposed high speed and idling jet extensions and said single discharge nozzle and finally only through said idling jet extension and said discharge nozzle responsive to increased engine speeds and corresponding variations of the fuel level in said fuel-metering receptacle.

2. A carburetor for internal combustion engines including a valve-controlled mixing chamber, an air inlet passage, a Venturi throat disposed between said air inlet passage and said mixing chamber, a constant-level fuel reservoir, a fuel well having a vertically disposed elongated opening providing for the passage of fuel into said well from said reservoir, said elongated opening providing also for air communication between said well and said reservoir above the reservoir fuel level, a second opening providing communication of the upper portions of said fuel reservoir and said well with said air inlet passage, a semi-buoyant fuel-metering receptacle mounted in said well and having a restricted fuel inlet in the lower portion thereof and an opening in the upper end thereof above the fuel level, fuel supply means extended into said Venturi throat comprising a pair of concentrically disposed high speed and idling fuel jets extending into said fuel-metering receptacle, said idling jet extension extending below the lower end of said high speed jet extension, an idling fuel outlet port adapted to discharge fuel into said mixing chamber, and a fuel passage connecting said idling fuel port with the idling jet, the flow of the fuel from said fuel-metering receptacle being adapted to be successively discharged through said idling fuel outlet port, thence through said pair of concentrically disposed high speed and idling jets and finally only through said idling jet responsive to increased engine speeds and corresponding variations of the fuel level of said fuel-metering device.

3. In a carburetor for internal combustion engines including a valve-controlled mixing chamber, an air inlet passage, a Venturi throat disposed between said mixing chamber and said air inlet passage, and an enclosed constant-level fuel reservoir; an enclosed fuel well open to air and fuel communication with said fuel reservoir, said fuel well having an open passage disposed above the fuel level in said fuel reservoir in open communication with said air inlet passage near said Venturi throat, a buoyant fuel-metering recep-

tacle mounted in said fuel well, an idling fuel jet having an idling fuel-discharge port in communication with said mixing chamber and having a fuel inlet end disposed within said fuel-metering receptacle, and a high speed fuel jet having a discharge nozzle disposed within said Venturi throat and having a fuel inlet end disposed within said fuel-metering receptacle, said idling jet having a branch discharge jet disposed within said high speed fuel discharge nozzle, said enclosed fuel reservoir and said enclosed fuel well being subjected to a partial vacuum induced therein by the flow of air past said open passage.

4. In a carburetor having a Venturi throat disposed between an air inlet passage and the fuel mixture chamber therein, a closed constant-level fuel reservoir, a buoyant fuel-metering receptacle operatively associated with said fuel reservoir having an open top and a fuel inlet opening for admission of fuel therein from said fuel reservoir, an idling fuel jet, a high speed fuel jet, an idling speed fuel port in open communication with said fuel mixture chamber, said idling and high speed fuel jets extending into said fuel-metering receptacle and having fuel inlet openings disposed at relatively different elevations with respect to the normal fuel level in said reservoir, a combined fuel-discharge nozzle extending into said Venturi throat adapted to discharge fuel from said high and idling speed jets, an extended passage from said idling speed jet to said idling speed port, and means whereby a partial vacuum is maintained in said closed reservoir and said fuel-metering receptacle during the operation of the carburetor, said difference in relative elevations of said high speed and idling speed jet inlets functioning to progressively decrease the discharge of the fuel from both of said jets through said nozzle during a range of progressively increased engine speeds responsive to a progressively lowering fuel level in said fuel-metering receptacle whereby the flow of the fuel through both of said jets is progressively decreased simultaneously with increased engine speeds within said range until a higher range of increased engine speeds beyond said first recited range of speeds is attained whereupon, due to the lowered fuel level in said fuel-metering receptacle, only the fuel admitted through the lower one of said jet inlet openings will be discharged from said nozzle.

5. In a carburetor for internal combustion engines having an air inlet passage provided with a Venturi throat and a throttle valve, and in combination, a constant-level fuel reservoir, a buoyant fuel-metering receptacle having a fuel inlet opening in the lower portion thereof for admitting fuel therein solely through said opening, a fuel jet comprising a hollow fuel discharge nozzle disposed in the Venturi zone, a tubular fuel-supply extension connected with said nozzle and having a fuel-inlet end disposed within said fuel-metering receptacle below the level of the fuel in said reservoir, a second tubular fuel-supply extension mounted within said first-named fuel-supply nozzle extension having a fuel-discharge end disposed within said nozzle and a fuel-inlet end extending into said fuel-metering receptacle below the fuel-inlet end of said fuel-supply nozzle extension, and an idling jet extension connected with said second tubular fuel-supply member and having a discharge port near the combustible mixture discharge opening of the carburetor.

6. In the combination embodied in claim 5, and including said constant-level fuel reservoir and

said fuel-metering receptacle enclosed in an air-tight housing to thereby provide and maintain a partial vacuum within said housing during the operation of the engine, said vacuum being induced through an opening in said housing which is open only to communication with the flow of air passing through said air inlet passage.

7. In a carburetor for internal combustion engines having an air inlet passage provided with a Venturi throat and a throttle valve, and in combination, an enclosed constant-level fuel reservoir and an enclosed fuel well in open fuel and air communication therewith, said fuel well having an opening in open communication with said air inlet passage whereby a variable partial vacuum is maintained within said enclosed fuel reservoir and within said enclosed fuel well during the operation of the engine, the partial vacuum increasing progressively relatively to the progressively increased speeds of the engine, an open-top cup-like buoyant fuel-metering receptacle mounted in said well and having a fuel-inlet opening in the bottom thereof, and fuel jet means disposed within said Venturi throat and extending into said fuel-metering receptacle, said fuel jet means having a plurality of fuel-inlet openings disposed at different elevations relatively to and below the constant fuel-level of said reservoir whereby the fuel discharged through said fuel jet means is admitted through a progressively decreased number of said fuel-inlet openings responsively to the progressively decreasing level of the fuel in said fuel-metering receptacle during progressively increased engine speeds and in a progressively decreased volumetric flow relatively to the progressively increased volumetric flow of air through said air inlet passage.

8. In a carburetor having a valve-controlled air passage, and including a constant-level fuel reservoir closed to atmospheric pressure during the operation of the carburetor, said fuel reservoir having passage means communicating with the flow of the air through said air passage whereby a variable partial vacuum is maintained in said fuel reservoir responsively to varying engine speeds, a buoyant fuel metering receptacle within said fuel reservoir, a Venturi throat in said valve-controlled air passage, a high speed jet, a low speed jet, both of said jets being disposed to discharge fuel into said Venturi throat and both of said jets having fuel-feeding extensions extending into said fuel metering receptacle, the fuel inlet end of said low speed jet extension extending below the fuel inlet end of said high speed jet extension whereby at certain advanced engine speeds and after the fuel level within said metering receptacle has been lowered below the inlet end of said high speed jet extension, fuel will then be fed into the Venturi throat only through the inlet end of said low speed jet extension, and means for admitting fuel into said fuel metering receptacle.

9. A carburetor for internal combustion engines including a mixing chamber having a valve-controlled outlet, a restricted Venturi throat below said mixing chamber, an air inlet passage communicating with said Venturi throat, a constant-level fuel reservoir having a float-controlled fuel inlet valve therein, an open passage providing air communication between said air inlet passage and said fuel reservoir, said fuel reservoir being sealed to atmospheric pressure except through said open passage when the carburetor is inoperative but subject to the induction of a partial vacuum therein by the flow of air past said open-

ing during the operation of the carburetor, a buoyant fuel-metering receptacle mounted for buoyant support in the fuel in said constant-level fuel reservoir and having an open top and a fuel-inlet opening in the lower portion thereof, a single fuel discharge nozzle, a pair of concentrically disposed high speed and idling fuel jet extensions having discharge ends arranged to discharge fuel through said single discharge nozzle into said Venturi throat and opposite ends extending into said fuel-metering receptacle, said idling jet extension extending below the lower end of said high speed jet extension, an idling fuel outlet port adapted to discharge fuel into said mixing chamber, and a fuel passage connecting said idling fuel port with said idling jet extension, the flow of the fuel from said fuel-metering receptacle being adapted to be successively discharged through said idling fuel outlet port, thence through said pair of concentrically disposed high speed and idling jet extensions and said single discharge nozzle and finally only through said idling jet extension and said discharge nozzle responsively to increased engine speeds and corresponding variations of the fuel level in said fuel-metering receptacle.

10. A carburetor for internal combustion engines including a valve-controlled mixing chamber, an air inlet passage, a Venturi throat disposed between said air inlet passage and said mixing chamber, a constant-level fuel reservoir, an opening providing communication of the upper portions of said fuel reservoir with said air inlet passage, a buoyant fuel-metering receptacle mounted for buoyant support in the fuel in said constant-level fuel reservoir and having a restricted fuel inlet in the lower portion thereof and an opening in the upper end thereof above the fuel level, fuel supply means extended into said Venturi throat comprising a pair of high speed and idling fuel jets having extensions extending into said fuel-metering receptacle, said idling jet extension extending below the lower end of said high speed jet extension, the flow of the fuel from said fuel-metering receptacle being adapted to be discharged through said pair of high speed and idling jets and finally only through said idling jet responsively to increased engine speeds and corresponding variations of the fuel level in said fuel-metering receptacle.

11. In a carburetor having a Venturi throat disposed between an air inlet passage and the fuel mixture chamber therein, a closed constant-level fuel reservoir, a buoyant fuel-metering receptacle operatively associated with said fuel reservoir having an open top and a fuel inlet opening for admission of fuel therein from said fuel reservoir, an idling fuel jet, a high speed fuel jet, said idling and high speed fuel jets extending into said fuel-metering receptacle and having fuel inlet openings disposed at relatively different elevations with respect to the normal fuel level in said reservoir, a combined fuel-discharge nozzle extending into said Venturi throat adapted to discharge fuel from said high and idling speed jets, and means whereby a partial vacuum is maintained in said closed reservoir and said fuel-metering receptacle during the operation of the carburetor, said difference in relative elevations of said high speed and idling speed jet inlets functioning to progressively decrease the discharge of the fuel from both of said jets through said nozzle during a range of progressively increased engine speeds responsively to a progressively lowering fuel level in said fuel-metering

receptacle whereby the flow of the fuel through both of said jets is progressively decreased simultaneously with increased engine speeds within said range until a higher range of increased engine speeds beyond said first-recited range of speeds is attained whereupon, due to the lowered fuel level in said fuel-metering receptacle, only the fuel admitted through the lower one of said jet inlet openings will be discharged from said nozzle.

12. In a carburetor for internal combustion engines having an air inlet passage provided with a Venturi throat and a throttle valve, and in combination, an enclosed constant-level fuel reservoir, said fuel reservoir having an opening in open communication with said air inlet passage whereby a variable partial vacuum is maintained within said enclosed fuel reservoir during the operation of the engine, the partial vacuum increasing progressively relatively to the progres-

sively increased speeds of the engine, an open-top cup-like buoyant fuel-metering receptacle mounted in said reservoir and having a fuel-inlet opening in the bottom thereof, and fuel jet means disposed within said Venturi throat and extending into said fuel-metering receptacle, said fuel jet means having a plurality of fuel-inlet openings disposed at different elevations relatively to and below the fuel level of said reservoir whereby 10 the fuel discharged through said fuel jet means is admitted through a progressively decreased number of said fuel-inlet openings responsive to the progressively decreasing level of the fuel in said fuel-metering receptacle during progressively increased engine speeds and in a progressively decreased volumetric flow relatively to the progressively increased volumetric flow of air through said air inlet passage.
